UNITED STATES PATENT OFFICE

2,690,007

SHAVING MECHANISM

William Jonathan Neidig, Napoleon, Ohio

Continuation of application Serial No. 572,807,
January 15, 1945. This application July 12,
1949, Serial No. 104,340

13 Claims. (Cl. 30—43)

1

My invention relates generally to cutlery and particularly to a shaving razor. Most particularly, my invention relates to an electric razor, that is a razor having relatively movable parts actuated by an electric motor means to effect shearing—the user merely moving the razor over the skin surface to be shaved.

Many of the general objects of my present invention are mentioned in my United States Letters Patent No. 2,367,686 issued January 23, 1945, this application being a continuation of application Serial No. 572,807 filed January 15, 1945, and since abandoned.

I have found it desirable, when using cooperating rotary and stationary cutter members engaging in a shearing cut contact, to maintain such contact with a minimum of interruption always, however, with provisions for assuring a maximum of freedom from injury to the user. One of the objects of my present invention is to supply improved means whereby this may be accomplished.

Another of the objects of the present invention is to reduce the wear upon the cutting elements through reduced interruption of contact, thereby increasing the cutting effectiveness of the razor, without increasing the danger of injury.

Another of my present objects is to provide an improved construction whereby the above-mentioned shearing advantages and safety provisions are combined with provisions enabling longer beard-ends to be cut off without an undesirable folding or thrusting back of the beard-ends upon themselves or into the skin.

In addition to the above stated general objects and corollary thereto, my invention has for one of its particular objects to provide a new and improved motor actuated rotary cutter member of cylindrical form adapted to be applied directly to a bearded skin. It is a further particular object of my invention to provide a rotary cutter member having a plurality of ridge-like portions of arcuate continuity extending coaxially about and radially projecting from the member's lateral surface, the spacing between adjacent ridge-like portions being such that only beard hairs are permitted ingress to the space between adjacent ridge-like portions—to the exclusion from said space of skin areas, both immediate and remote from the bases of the interspace protruding beard hairs. Thus, a rotary cutter member embodying my invention is characterized by having its ridge-like portions spaced a distance determined by that space required to allow protrusion of beard hairs into the space between adjacent

2

ridge-like portions without permitting intrusion into said space of skin area, both that which is immediate and remote to the bases of the interspace protruding beard hairs.

More particularly, my invention has for an object to provide a rotary cutter member characterized by the fact that the spacing between adjacent ridge-like portions is of a dimensional magnitude between $\frac{8}{1000}$ and $\frac{30}{1000}$ inch. I acknowledge that one of my predecessors in the shaving instrument art, namely Hiskey of United States Letters Patent No. 1,033,321, has suggested the use of a ridged, cylindrical rotary cutter member adapted to be motor actuated and applied directly for shaving to the bearded skin. Hiskey, however, designed the spacing of his adjacent ridges so that the skin area immediate to the bases of the interspace protruding beard hairs to be cut also protrudes into the space between the ridges. This condition of allowing interspace skin protrusion was essential to the operation of the Hiskey shaver. Further, by reason of the position of the Hiskey cutting blades against the lateral surface of his cylindrical member and the absence of a stationary cutter in cooperating and bridging relation with the rotary cutter, the so protruding skin area was not placed in any unusual peril of being cut in the Hiskey razor. However, Hiskey's construction does not lend itself to cooperating with a stationary cutter and has certain inherent faults, remedied by my present invention. One of the chief faults of the Hiskey construction is that of causing the beard hairs, about to be sheared, to be pressed back into the skin or bent upon themselves by reason of engagement of the beard hair ends with the portions of the lateral surface of the rotary member intermediate the ridges. In embodiments of my invention, I overcome this disadvantage by spacing my cutting element on the cutter member away from the lateral surface of the member, thereby providing room into which the beard hairs may extend freely and un-bent, in the path of the cutting element.

Hence, another particular object of my invention is to provide a rotary cutter member having a cutting element and means for mounting the element on the member bearing surfaces in spaced relation to the lateral surface of the cutter member and in bridging or spanning relation to the space between adjacent ridge-like portions thereof. Thus, the interspace protruding beard hairs may extend in the path of movement of the cutting element, for shearing.

A further particular object is to provide a ro-

tary cutter member characterized by the fact that the ridge-like portions extend in helical continuity about the member's lateral surface and with respect to the axis of rotation of the member. Thus, the ridge-like portions progressively feed beard hairs to the cutting element, as the member is moved translatorily over a bearded skin in directions normal to the member's axis of rotation.

The invention consists in other features and advantages which will appear from the following description and upon examination of the drawing. Structures containing the invention may partake of different forms and still embody the invention. To illustrate a practical application of the invention, I have selected preferred and modified forms of a shaving mechanism as examples of the various structures and details thereof that contain the invention and shall describe the selected structures hereinafter. It is understood that variations may be made without departing from the spirit of the invention. The particular structures selected are shown in the accompanying drawing and described herein-after.

Fig. 1 of the accompanying drawing is a front view of a preferred form of embodiment of my invention with portions of the casing being shown broken away. Fig. 2 is a view, greatly enlarged, of a section on the line 2—2 indicated in Fig. 1, with portions of the casing shown intact and a portion of the cutting element shown removed. Fig. 3 is a detail view, similarly enlarged, of the rotary cutter member shown in Figs. 1 and 2. Fig. 4 is a detail enlarged view of a modified form of a rotary cutter member embodying certain features of my invention. Fig. 5 is a view partly in section of a portion of the rotary cutter member shown in Fig. 4.

The embodiments of my invention shown in the drawing are each adapted to be driven by a small and conventional electric motor and each employ cooperating rotary and stationary cutter members. The invention, however, is not limited to any particular form of drive or stationary cutter member, but is directed, in the main, to the rotary cutter member and cutting element mounted thereon and the relation thereof to the stationary cutter member.

The motor shown receives power through electric wires 1 and is supported in the casing 2. The rotor of the motor is mounted upon shaft 3, journaled as at 4, in casing 2. The usual starting and stopping thumb-wheel 5 may be provided on shaft 3, in the instance that the motor is not provided with self-starting means. Also attached to the shaft 3 is bevel gear 6, indicated diagrammatically, which meshes with bevel gear 7, also indicated diagrammatically, on axle 8. The axle 8 is journaled in an extension 11 of casing 2. By this construction, a rotary cutter member 9, embodying my invention, mounted on and keyed to axle 8 may be supported for actuation in a position of convenience to the user in shaving.

The rotary cutter member 9 is a cylindrical member and preferably of small diameter. It has a plurality of ridge-like portions 13 of arcuate continuity extending coaxially about and radially projecting from axially spaced points on the lateral surface of the cutter member 9. In the preferred form shown in Figs. 2 and 3, the ridge-like portions 13 extend in helical arcuate continuity at a high axial angle around and along the member's lateral surface from one to the other end thereof. In the modified form

shown in Figs. 4 and 5, the ridge-like portions 13' extend in annular arcuate fluting-like continuity about the lateral surface of the cutter member 9'.

5 The points on the lateral surface of the cutter member 9 from which adjacent ridge-like portions 13 project are critically spaced in embodiments of my invention. This spacing defines a groove or space 15 between adjacent portions 13 which, measured axially of the member, is determined by that distance or spacial relation required to allow beard hairs to project into the space 15, without permitting intrusion into such space 15 of skin areas immediately adjacent or remote from the bases of the beard hairs protruding into the space—as a consequence of placing the cutter member 9 against a bearded skin for shaving. Thus, adjacent portions 13 may be regarded as skin-bearers adapted to surface engage skin areas on opposite sides of and adjoining a skin area from which the beard hairs, protruding into beard receiving spaces 15, extend. The portions 13 in engaging the adjoining skin areas tend to draw the intermediate area 15 somewhat taut, in spanning relation to the space 15, preventing sag or flexure of the intermediate skin area into said space. The reason for this provision will become more apparent as the description proceeds.

30 I have found that such spacing stated dimensionally should be of a magnitude between $\frac{3}{1000}$ and $\frac{3}{4000}$ inch, for best results. When the spacing is less, the beard hairs enter the space 15, only with difficulty, and when the spacing is greater, the skin will flex or wrinkle into the space.

35 It will be noted from the drawing that ridge-like portions 13 have substantially flat crown surfaces which give increased skin traction to the mentioned adjoining skin areas and aid materially in exerting a tautening force to the intermediate skin area. The crown surfaces are preferably of a width between $\frac{1}{50}$ and $\frac{1}{80}$ inch. The relations described in reference to the preferred form of my invention also exist in the modified form shown in Figs. 4 and 5. There the portions 13' have the preferred dimensional width and are spaced on member 9' to provide space 15' of the same critical spacing and dimension between adjacent portions as that described with reference to portions 13 on member 9.

40 In order to provide member 9 with cutting means, a lineal element, such as the wire 12, is mounted on the member. The wire element 12 has a sharpened lineal edge 12a in plane with the outermost lateral surface thereof as viewed in Fig. 2. The element 12 extends in helical lineal continuity at a low axial angle about an axis and radially spaced therefrom a distance substantially equal to the arcuate radius of the portions 13. Thus, the element 12 may be placed over and will substantially fit about the member 9, traversing the portions 13. As shown in Fig. 3, the element 12 has end eyes adapted to enclose opposite reduced end portions 18 of member 9 and forming parts of the means for connecting the element 12 to member 9. If desired, clamping nuts 17, threaded on portions 18, may be utilized to seize the end eyes of element 12.

45 In addition to the mentioned end eyes of element 12, the means for connecting the element 12 to the member 9 includes the provision of a bearing surface 16 on each adjacent ridge-like portion 13. The bearing surface 16 is formed by a notch in the periphery of each portion 13, which in relation to notches in adjacent por-

tions 13 are aligned in helical sequence approximating the helical extension of the element 12, forming, in a sense, a helical groove in the peripheries of the portions 13 of low axial angle. The depth of each notch and, hence, the disposition of the bearing surface 16 provided thereby, is of critical significance in embodiments of my invention.

Stated in one way the bearing surface 16 is located a radial distance from the periphery of its respective ridge-like portion 13 less than the radial distance between such periphery and the lateral surface of the member 9, that is the bottom surface of the space 15. Thus, the bearing surface 16 of adjacent portions 13 will support the element 12 in spaced relation to the member's lateral surface and in bridging or spanning relation to the space 15. From another standpoint, namely, that of the transverse thickness of the element 12, the bearing surface 16 is located a radial distance inwardly of the ridge-like portion's periphery to locate the cutting edge 12a preferably in the arc and flush with the crown surface of its respective portion 13 or slightly (not in excess of $\frac{1}{1000}$ inch) protruding therefrom.

Cutter element 12 may be constructed in many ways. In the illustrated embodiment shown in Fig. 3 it is formed of elongated material, such as music wire, ground down to form edged slabs of semi-circular section or thinner with cutting edge 12a. The cutter element may be constructed quite thin and still remain strong, since it is given adjacent support in portions 13 throughout its length as described.

In constructing member 9 of Fig. 3 or the member 9' of Fig. 4, use may be made either of laminated construction in which shaped sheets 19 and 20 of suitable material are assembled in alternate sequence, or the member may be fashioned from solid material. One of the advantages of the present construction is that member 9 may be made from relatively soft and easily workable material upon which a cutter element of grindable and temperable material may readily be assembled for cooperation, thus joining cutting excellence with economy of manufacture.

The stationary cutter 14 and its supporting structure as illustrated herein are shown most clearly in Fig. 2. The cutter 14 is shown as being of L section, to enable it to be used in narrow situations close to the skin. In this form a shelf-like blade portion 21 is joined at an angle to an upwardly-extending wall-like portion 22, the construction being mounted to rock upon projecting axles 23 at either end, the axles being journaled in end portions 24 of a removable box-like support 25. Upwardly-extending portion 22 of the cutter is pressed against by light springs 26, seated in pockets 27 in frame extension 11. Screws 28 conveniently hold support 25 in place against frame extension 11. The arrangement is such that when support 25 is in place, springs 26 act to press the cutting edge of cutter 14 into sliding contact with the edge portions of cutter element 12, which cut off the beard-ends shearingly and sweep them past cutter 14 into a debris chamber 29 behind. The action is aided by centrifugal force, which ejects the debris from the spaces 15 into the chamber 29. Chamber 29 is formed in part by frame extension 11 and in part by cutter 14 and support 25. As will be seen, by lifting away removable support 25, the cutter 14 is also removed and debris chamber 29 is left

entirely open for cleaning. The construction supplies an especially compact form of stationary cutting means that is useful in other shaving mechanisms. The invention described, however, is not dependent upon any particular form of stationary cutter, nor is it dependent upon spring means for holding the stationary and rotary cutters in shearing engagement.

In operation, the user grasping the case 2 and 10 starting the rotor shaft 3 by spinning wheel 5, applies the rotating skin supporting member to bearded skin, preferably with a light pressure and so that member 9 extends normal to the "grain" of the beard, the "grain" of the beard 15 being the up-down-side direction of growth on the skin. The rotation of member 9 being counter-clockwise as viewed in Fig. 2, the ridge-like portions 13 track over the skin, marshalling the beard ends into the helical groove or spaces 20 15 to direct them to positions where they are sheared by coaction of cutting element 12 and stationary cutter 14. The sheared end debris is then cast to the chamber 29, as heretofore explained.

25 By reason of the described spacial relation between adjacent ridge-like portions, only beard hair will be directed to the point of shear contact between element 12 and cutter 14, the skin being restrained from injury. Also to be noted 30 is the fact that in the relation of cutting element 12 and cutter 14, a continued contact will be maintained uninterrupted, at advantageous shear angle.

The modified form of rotary cutter member 35 shown in Figs. 4 and 5 has many of the features of the preferred form. The difference of the continuity of the ridge-like portions 13' in annular arcuate relation instead of helical has already been mentioned. Further than that, the modified form has a plurality of cutting elements 12', each in the form of edged blades of different pitch of helical extension than the element 12. The blade elements 12' are preferably of regular polygonal form in transverse section, being thicker than element 12, and having a cutting edge 45 12a' in plane with an outermost lateral surface, as viewed in Fig. 5. As a consequence the notches in portions 13' providing bearing surfaces supporting the elements 12' are somewhat deeper in 50 portions 13' than those in portions 13. Also, the elements 12 have end shanks engaged by a threaded thimble 17' to lock the elements onto the ends of member 9'.

In operation, however, the member 9' acts in 55 much the same manner as that described in connection with the preferred form, except the marshalling advantage of helical extending portions 13 are not obtained in the annular portions 13' and there will be short periods of interrupted contact between the cutter 14 and elements 12'. The cutting edges 12a', like the cutting edge 12a, are sustained in spaced relation to the lateral surfaces of the member 9' and to the bottoms of each of the spaces 15' to secure 60 65 the same close cut and room for beard extension provided in the preferred form.

While I have illustrated and described the best forms of my invention now known to me, as required by the statutes, those skilled in the art will readily understand that changes may be made in the disclosed construction without departing from the spirit of my invention as set forth in the appended claims.

I claim:

1. In a shaving mechanism employing coop-

erating rotary and stationary cutters, in combination: a rotary cutting and skin-supporting member of cylindrical form having a groove extending obliquely about its periphery at a high axial angle and having a groove extending obliquely along its periphery at a low axial angle, said groove crossing the groove of high angle; the groove of high angle being defined by smooth skin-supporting bearer surfaces having an arcuate concentric relation to the axis of rotation of said member and forming beard-receiving recesses below cutting level; the bearer surfaces forming skin supports limiting the entry of skin surfaces into the recesses; the groove of low angle extending from end to end of the member and having a cutter seated therein; the cutter having smooth cutting portions at least as high as the bearer surfaces, said cutting portions forming shearing edges across the recesses.

2. In a shaving mechanism employing cooperating rotary and stationary cutters, in combination: a rotary cutting and skin-supporting member of cylindrical form having grooves extending obliquely about its periphery at a high axial angle and having grooves extending obliquely along its periphery at a low axial angle, said grooves crossing the grooves of high angle; the grooves of high angle being defined by smooth skin-supporting bearer surfaces and forming beard-receiving recesses below cutting level; the bearer surfaces forming skin supports limiting the entry of skin surfaces into the recesses; the grooves of low angle extending from end to end of the member and having cutters seated therein; the cutters having smooth cutting portions at least as high as the bearer surfaces, said cutting portions forming shearing edges across the recesses; and a stationary cutter having a smooth long edge portion in cooperating shearing contact with said shearing edges.

3. In a shaving mechanism employing cooperating rotary and stationary cutters, in combination: a rotary cutting and skin-supporting member of cylindrical form having grooves extending obliquely about its periphery at a high axial angle and having grooves extending obliquely along its periphery at a low axial angle, said grooves crossing the grooves of high angle; the grooves of high angle being defined by smooth-surfaced skin-supporting bearer structure and forming beard-receiving recesses below cutting level; the bearer structure forming skin supports limiting the entry of skin surfaces into the recesses; the grooves of low angle extending from end to end of the member and having peripheral shearing cutters seated therein; the cutters having smooth peripheral portions and smooth shearing portions flush therewith; and a stationary cutter having a smooth long edge portion in cooperating shearing contact with said peripheral cutters.

4. In a shaving mechanism, a rotary cutter comprising a rotatable member of cylindrical form having a plurality of ridges and recesses laterally encircling the member and in alternating axial succession therealong and a lineally extending element having a cutting edge along its length and a plurality of surface areas at spaced points along said element length, said plurality of ridges having a bearing surface adapted to engage said element surface areas and thereby mount the element on the member, said ridge bearing surface being radially outward of axially adjacent floor portions of the thereto adjoining recess to thereby support, when engaging said element surface areas, the portions

10
15

of the element between said element surface areas in a position extending across the recesses in radially spaced relation to and above the recess floors, each of the last named ridges having a crown of continuously concentric arcuate relation to the axis of member cylindricity and radially spaced from said ridge bearing surface a distance not in excess of the element thickness in the regions of said element at which said element surface areas are located whereby the crown of each ridge extends and moves through an arc parallel to the orbit through which said element moves on rotation of the member.

5. In a shaving mechanism, the rotary cutter described in claim 4 in which each said ridge crown is a flat surface and originates on one side of said ridge bearing surface at a circumferential point on the member substantially coincident with the disposition of the element cutting edge when the said ridge bearing surface engages said element surface area in mounting the element on the member whereby said ridge crown surface limits engagement of the element cutting edge in the region of element and ridge engagement.

6. In a shaving mechanism, the rotary cutter described in claim 5 in which said element also has a rear edge and in which each said ridge crown surface terminates on the other side of said ridge bearing surface at a circumferential point substantially coincident with the disposition of said rear edge of the element when the said ridge bearing surface engages said element surface area in mounting the element on the member whereby said ridge substantially encloses the element in the region of element and ridge engagement.

7. In a shaving mechanism, the rotary cutter described in claim 6 in which said element has a face extending between said cutting and rear edges thereof and in which the originating and terminating points of said ridge crown surfaces circumferentially adjoining said ridge bearing surface are circumferentially spaced a distance substantially equal to that through which said element face extends between said element edges whereby said element face circumferentially joins the points of origin and termination of said ridge crown surfaces on opposite sides of said ridge bearing surface in a concentric arcuate continuity when the surface area of said element engages said ridge bearing surface.

8. In a shaving mechanism, the rotary cutter described in claim 4 in which said plurality of ridges and recesses are of a helical continuity with respect to the axis of cylindricity of said member.

9. In a shaving mechanism, the rotary cutter described in claim 8 in which said element is of helical continuity with respect to the axis of cylindricity of said member.

10. In a shaving mechanism, the rotary cutter described in claim 9 in which the helical continuity of the element is at a steeper pitch relative to the axis of member cylindricity than the pitch of helical continuity of said plurality of ridges and recesses with respect to said axis.

11. In a shaving mechanism, the rotary cutter described in claim 4 in which said ridges are axially spaced from each other a distance between $\frac{1}{1000}$ and $\frac{3}{1000}$ inches measured axially of said member and each ridge crown is a flat surface measuring axially of said member between $\frac{1}{50}$ and $\frac{1}{80}$ inches.

12. In a shaving mechanism, the rotary cut-

9

ter described in claim 4 in which the ridge crown is radially spaced from said ridge bearing surface a distance substantially equal to and not less than .002 inches less than the thickness of the element in the regions of the element surface areas whereby said element cutting edge will be supported substantially flush with and not more than .002 inches radially outward of the ridge crown.

13. In a shaving mechanism, the rotary cutter described in claim 4 in which said element comprises a wire having a sharp lineally extending edge with an arcuate flat side and an opposite rounded side, said element surface areas being band-like areas occurring at spaced points along and on said rounded side, said ridge bearing surface being of a mating contour and di-

5

10

mension with said element surface areas whereby the element in effect fits on and into the ridges of the member.
